Primary Examiner — Sandra Snapp(74) *Attorney, Agent, or Firm* — Sterne, Kessler, Goldstein & Fox P.L.L.C.(57) **CLAIM**

The ornamental design for a seating unit, as shown and described.

DESCRIPTION

FIG. 1 is a perspective view of a seating unit showing our new design.

FIG. 2 is another perspective view thereof;

FIG. 3 is another perspective view thereof;

FIG. 4 is another perspective view thereof;

FIG. 5 is another perspective view thereof;

FIG. 6 is another perspective view thereof;

FIG. 7 is another perspective view thereof;

FIG. 8 is a perspective view of a second embodiment of a seating unit showing our new design; and,

FIG. 9 is another perspective view thereof.

The broken lines in the Figures show environment for illustrative purposes and form no part of the claimed design.
